PORABLE ELECTRIC DRILL UNIT

Robert O. Ernest, Oak Park, Ill., assignor to Sunbeam Corporation, Chicago, Ill., a corporation of Illinois

Application June 24, 1955, Serial No. 36,665

Term of patent 14 years

(Cl. D54—14)

Fig. 1.

Fig. 2.

Fig. 3.

Fig. 4.

Fig. 1 is a side elevational view of a portable electric drill unit embodying my new design;

Fig. 2 is a front elevational view of the drill unit of Fig. 1;

Fig. 3 is a top plan view of Fig. 1; and

Fig. 4 is a rear elevational view of Fig. 2.

I claim:

The ornamental design for a portable electric drill unit, substantially as shown.
